SLAB THROWER

Harrel E. Hutchinson, Myrtle Point, Oreg., assignor of one-half to Henry C. Rowell, Myrtle Point, Oreg.

Application November 13, 1953, Serial No. 391,829

11 Claims. (Cl. 198—128)

This invention relates to a portable slab thrower adapted to be utilized in conjunction with stationary or portable saw mills to dispose of waste slabs in such manner that the slabs will be thrown a considerable distance from the milling operation so as to eliminate the necessity of the slabs being burned during the seasons when statutes prohibit the burning of slabs.

The primary object of this invention resides in the provision of a portable apparatus which is adapted to receive slabs coming from the mill and to forcefully project the slabs away from the mill site whereby the slabs will be deposited a considerable distance from the mill site.

The construction of this invention features an open top trough-like housing which has the feed conveyor adapted to receive slabs from the mill. This feed conveyor carries the slabs onto a drum having teeth therein which teeth are designed to both lift the slabs and to catch the rear portions of the slabs so as to forcefully eject the slabs into the air and throw them a considerable distance. There is also provided an alignment and discharge conveyor which acts in conjunction with the drum to aid in the ejection of the slabs while providing means for holding the slabs in alignment with the drum so that the slabs may be more forcefully ejected.

Two forms of the invention are to be hence forth disclosed, one of which utilizes a guide conveyor which is adapted to aid in the guiding of the slabs into engagement with the drum. Another of the forms of the invention includes a guide plate positioned beneath the feed conveyor and to the rearward of the drum.

Still further objects and features of this invention resides in the provision of a slab thrower that is strong and durable, simple in construction and operation, capable of being transported from one saw mill site to another, as may be necessary, and which is comparatively inexpensive to construct thereby enabling wide use of such device.

These, together with the various ancillary objects and features of the invention which will become apparent as the following description proceeds are attained by this slab thrower, preferred embodiments of which have been illustrated in the accompanying drawings, by way of example only, wherein:

Figure 1 is a top plan view of the slab thrower comprising the present invention;

Figure 2 is a rear elevational view of the apparatus;

Figure 3 is a front elevational view of the slab thrower;

Figure 4 is a side elevational view of the slab thrower illustrating in particular, the motor which provides the means for driving the various elements of the slab thrower;

Figure 5 is another side elevational view looking at the other side of the slab thrower than that shown in Figure 4;

Figure 6 is a sectional detail view as taken along the plane of line 6—6 in Figure 5 and illustrating in particular, the construction of the belt tightener utilized in maintaining the belt drive means taut;

Figure 7 is a vertical sectional view as taken along the plane of line 7—7 in Figure 1 and illustrating the internal arrangement of parts of one form of the invention; and

2

Figure 8 is a sectional detail view similar to that of Figure 7 but illustrating a modified form of the invention.

With continuing reference to the accompanying drawings wherein like reference numerals designate similar parts throughout the various views, reference numeral 10 generally designates a first form of slab thrower which is illustrated in Figures 1 through 7. The slab thrower 10 includes a housing 12 which is open at the top and which has attached thereto outwardly and upwardly diverging receiving guide flange 14 and 16. The housing 12 may be constructed from plates attached to an angle or channel iron framework and may be suitably braced as may be desirable as at 18. A pair of channel iron longitudinal support members 20 are provided for supporting the housing and for providing means whereby the entire slab thrower can be moved to properly adjust the slab thrower in situ. A platform 22 is connected to the housing for supporting a motor 24 which provides the motor power for the apparatus. Obviously, the motor 24 can be of the internal combustion type such as gasoline or diesel powered or may be steam or electric powered.

Suitably journaled on brackets secured to the housing 12 are a pair of shafts 26 and 28 carrying cylindrical drums 30 and 32 about which an endless belt substantially 25 horizontal feed conveyor 34 is entrained. The feed conveyor 34 is positioned at such height where it can be properly aligned with a conveyor as at 36 leading from the saw mill for delivery of slabs thereto. Mounted on the shaft 28 is a pulley 38.

30 Mounted on a shaft 40 journaled in the bearings mounted on the housing is a drum 42 of comparatively rigid construction which has a plurality of teeth 44 which are arranged in staggered rows that are angularly spaced along the periphery of the drum 42 and which are of substantially triangular shape. The shaft 40 and the drum 42 is driven by the motor 24 by means of an endless belt 46 entrained about a pulley wheel 48 mounted on the shaft 40 and a pulley wheel 50 mounted on the stub shaft of the motor 24. It is to be noted that the shaft 40 comprises the drive shaft of the drive means for the endless belt conveyor 34 and for the endless belt discharge conveyor 52 mounted at the forward discharge end of the housing 12 are about drums 54 and 56 mounted on shaft 58 and 60, respectively. The shafts 58 and 60 are suitably journaled in bearings carried by brackets attached to the housing of suitable construction. It is to be noted that the conveyor 52 is positioned in front of and extends upwardly and forwardly from the drum 42 so that it may both aid in the discharge of the slabs while maintaining the slabs in proper alignment so that the teeth 44 can engage the rear ends of the slabs to impart enough force thereon to impel the slabs a considerable distance from the slab thrower 10.

55 The shaft 60 has mounted thereon a pulley 62. Mounted on the shaft 40 is a set of pulleys 64. Entrained about the pulleys 62 and 64 is an endless belt 66 and another endless belt 68 is likewise entrained about the pulleys 38 and 64 to impart motion to the shafts 60 and 28, respectively. A generally V-shaped wire mesh cage 70 is positioned on the outside of the housing 12 over the respective pulleys and belts for protective purposes. It is noted that the drive means for the slab thrower are generally mounted outwardly of the housing 12, this comprising an important part of the invention since it protects the working parts thereof.

60 Mounted on a pair of supports 72 is an upwardly and forwardly extending guide plate or platform 74 which is positioned to the rear of the drum 42 and extends below the feed conveyor 34. In lieu of the guide plate 74, there is shown in Figure 8 a modified form of the invention 70 which includes a rearwardly feeding guide conveyor 76 mounted on drums 78 and 80, the guide conveyor being

positioned below and to the rear of the drum 42 and being below the feed conveyor 34.

It is to be noted that the belt 46 is encased in a wire mesh guard, as at 82.

In either the embodiment as shown in Figures 1 through 7 or the embodiment as is shown in Figure 8, there may be utilized a plurality of fingers formed of rods, as indicated at 84 and attached to a mounting plate 86 held in alignment with the discharge conveyor 52, the rods 84 forming fingers adapted to intermesh with the teeth 54 so that if a slab were to be caught on the teeth, it could be freed readily therefrom.

The operation of this slab thrower is quite simple. A slab received from conveyor 36 is carried by the conveyor 34 until such time as it is directed on to the drum 42 with the end portion thereof falling on the guide plate 74. The teeth 44 will then pull the slab on to the conveyor 52, the rods 84 serving to free the teeth 44 from the slab should the teeth bite deeply into the slabs. Then, the conveyor 52 will carry the slab upwardly until such time as the teeth 44 can engage the surface of the slab and impel it outwardly with great force so that the slab which is headed upwardly and outwardly will be thrown a considerable distance from the slab thrower. It is to be realized that the drum 42 is revolving at a considerable rate.

The operation of the embodiment of the invention, as is shown in Figure 8, is quite similar. After the conveyor 34 has carried the slab, it will permit the forward end of the slab to fall onto the conveyor 76, depending, of course, upon the length of the slab. Then, the slab has the lowermost end thereof carried rearwardly until the slab abuts against the transverse guide rod or bar 88 extending between the sides of the housing. This will cause the slab to fall over and onto the drum 42 upon further movement of the backwardly feeding guide conveyor 76 thereby permitting the teeth 44 of the drum, to lift the slab onto the conveyor 52 which then aids in the carrying of the slab upwardly and outwardly until the teeth 44 can engage the surface of the slab in such manner as to properly propel the slab.

Since from the foregoing the construction and advantages of the slab thrower are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to which fall into the scope of the appended claims.

What is claimed as new is as follows:

1. A slab thrower comprising a substantially trough-shaped housing having feed and discharge ends and having an open top, a feed conveyor in said housing adjacent said feed end thereof, a drum rotatably mounted in said housing adjacent the discharge end thereof and having a plurality of teeth attached thereto, means between said drum and said feed conveyor for receiving a slab from said feed conveyor and delivering the slab to said drum, an angularly upwardly extending alignment and discharge conveyor positioned at the discharge end of said housing, said discharge conveyor extending upwardly above said drum, and drive means for actuating said drum, said feed conveyor and said discharge conveyor.

2. A slab thrower comprising a substantially trough shaped housing having rear feed and forward discharge ends and having an open top, a pair of outwardly and upwardly diverging receiving guide flanges secured to the upper parts of said housing, a substantially horizontally extending forward feeding endless belt feed conveyor in said housing adjacent said feed end thereof, a drum rotatably mounted in said housing adjacent the discharge end thereof and having a plurality of teeth attached thereto, an angularly outwardly and forwardly extending and forwardly and upwardly feeding endless belt alignment

and discharge conveyor positioned in front of said drum, a forwardly and upwardly extending guide plate positioned to the rear of said drum and below said feed conveyor, and means for actuating said drum, said feed conveyor, and said discharge conveyor.

3. A slab thrower comprising a substantially trough shaped housing having rear feed and forward discharge ends and having an open top, a pair of outwardly and upwardly diverging receiving guide flanges secured to the upper parts of said housing, a substantially horizontally extending forward feeding endless belt feed conveyor in said housing adjacent said feed end thereof, a drum rotatably mounted in said housing adjacent the discharge end thereof and having a plurality of teeth attached thereto, an angularly upwardly and forwardly extending and forwardly and upwardly feeding endless belt alignment and discharge conveyor positioned in front of said drum, a rearwardly feeding substantially horizontal slab guiding conveyor positioned behind said drum and below said feed conveyor, a guide rod secured to said housing above said guide conveyor, and means for actuating said drum, said feed conveyor, and said discharge conveyor.

4. A slab thrower comprising a substantially trough shaped housing having feed and discharge ends and having an open top, a feed conveyor in said housing adjacent said feed end thereof, a drum rotatably mounted in said housing adjacent the discharge end thereof and having a plurality of teeth attached thereto, an angularly upwardly extending alignment and discharge conveyor positioned at the discharge end of said housing, said discharge conveyor extending upwardly above said drum, and drive means for actuating said drum, said feed conveyor, and said discharge conveyor, a plurality of spaced fingers positioned above said drum and in alignment with said discharge conveyor, said fingers intermeshing with said teeth.

5. A slab thrower comprising a substantially trough shaped housing having rear feed and forward discharge ends and having an open top, a pair of outwardly and upwardly diverging receiving guide flanges secured to the upper parts of said housing, a substantially horizontally extending endless belt feed conveyor in said housing adjacent said feed end thereof, a drum rotatably mounted in said housing adjacent the discharge end thereof and having a plurality of teeth attached thereto, an angularly upwardly and forwardly extending endless belt alignment and discharge conveyor positioned in front of said drum and extending upwardly above said drum, and means for actuating said drum, said feed conveyor, and said discharge conveyor, a plurality of spaced fingers positioned above said drum and in alignment with said discharge conveyor, said fingers intermeshing with said teeth.

6. A slab thrower comprising a substantially trough shaped housing having rear feed and forward discharge ends and having an open top, a pair of outwardly and upwardly diverging receiving guide flanges secured to the upper parts of said housing, a substantially horizontally extending forward feeding endless belt feed conveyor in said housing adjacent said feed end thereof, a drum rotatably mounted in said housing adjacent the discharge end thereof and having a plurality of teeth attached thereto, an angularly upwardly and forwardly extending and forwardly and upwardly feeding endless belt alignment and discharge conveyor positioned in front of said drum, a forwardly and upwardly extending guide plate positioned to the rear of said drum and below said feed conveyor, and means for actuating said drum, said feed conveyor, and said discharge conveyor, a plurality of spaced fingers positioned above said drum and in alignment with said discharge conveyor, said fingers intermeshing with said teeth.

7. A slab thrower comprising a substantially trough shaped housing having rear feed and forward discharge ends and having an open top, a pair of outwardly and

upwardly diverging receiving guide flanges secured to the upper parts of said housing, a substantially horizontally extending forward feeding endless belt feed conveyor in said housing adjacent said feed end thereof, a drum rotatably mounted in said housing adjacent the discharge end thereof and having a plurality of teeth attached thereto, an angularly upwardly and forwardly extending and forwardly and upwardly feeding endless belt alignment and discharge conveyor positioned in front of said drum, a rearwardly feeding substantially horizontal slab guiding conveyor positioned behind said drum and below said feed conveyor, a guide rod secured to said housing above said guide conveyor, and means for actuating said drum, said feed conveyor, and said discharge conveyor, a plurality of spaced fingers positioned above said drum and in alignment with said discharge conveyor, said fingers intermeshing with said teeth.

8. A slab thrower comprising a substantially trough-shaped housing having feed and discharge ends and having an open top, a feed conveyor in said housing adjacent said feed end thereof, a drum rotatably mounted in said housing adjacent the discharge end thereof and having a plurality of teeth attached thereto, means between said drum and said feed conveyor for receiving a slab from said feed conveyor and delivering the slab to said drum, an angularly upwardly extending alignment and discharge conveyor positioned at the discharge end of said housing, said discharge conveyor extending upwardly above said drum, and drive means for actuating said drum, said feed conveyor and said discharge conveyor, said drive means being supported outwardly of said housing.

9. A slab thrower comprising a substantially trough shaped housing having rear feed and forward discharge ends and having an open top, a pair of outwardly and upwardly diverging receiving guide flanges secured to the upper parts of said housing, a feed conveyor in said housing adjacent said feed end thereof, a drum rotatably mounted in said housing adjacent the discharge end thereof and having a plurality of teeth attached thereto, an angularly upwardly extending alignment and discharge conveyor positioned at the discharge end of said housing, said discharge conveyor extending upwardly above said drum, and drive means for actuating said drum, said feed conveyor, and said discharge conveyor, said drive means being supported outwardly of said housing, a plurality of

spaced fingers positioned above said drum and in alignment with said discharge conveyor, said fingers intermeshing with said teeth.

5 10. A slab thrower comprising a substantially trough shaped housing having rear feed and forward discharge ends and having an open top, a pair of outwardly and upwardly diverging receiving guide flanges secured to the upper parts of said housing, a substantially horizontally extending forward feeding endless belt feed conveyor in said housing adjacent said feed end thereof, a drum rotatably mounted in said housing adjacent the discharge end thereof and having a plurality of teeth attached thereto, an angularly upwardly and forwardly extending and forwardly and upwardly feeding endless belt alignment and discharge conveyor positioned in front of said drum, a forwardly and upwardly extending guide plate positioned to the rear of said drum and below said feed conveyor, and means for actuating said drum, said feed conveyor, and said discharge conveyor, said drive means being supported outwardly of said housing.

20 11. A slab thrower comprising a substantially trough shaped housing having rear feed and forward discharge ends and having an open top, a pair of outwardly and upwardly diverging receiving guide flanges to the upper parts of said housing, a substantially horizontally extending forward feeding endless belt feed conveyor in said housing adjacent said feed end thereof, a drum rotatably mounted in said housing adjacent the discharge end thereof and having a plurality of teeth attached thereto, an angularly upwardly and forwardly extending and forwardly and upwardly feeding endless belt alignment and discharge conveyor positioned in front of said drum, a rearwardly feeding substantially horizontal slab guiding conveyor positioned behind said drum and below said feed conveyor, a guide rod secured to said housing above said guide conveyor, and means for actuating said drum, said feed conveyor, and said discharge conveyor, said drive means being supported outwardly of said housing.
